UNITED STATES PATENT OFFICE.

CHARLES MYERS, OF EUGENE, OREGON.

PHOTOGRAPHIC FLASH-LIGHT.

1,189,215.

Specification of Letters Patent. Patented June 27, 1916.

Application filed August 9, 1913, Serial No. 783,939. Renewed May 23, 1916. Serial No. 99,429.

To all whom it may concern:

Be it known that I, CHARLES MYERS, a citizen of the United States of America, residing in Eugene, in the county of Lane and 5 State of Oregon, have invented certain new and useful Improvements in Photographic Flash-Lights, of which the following is a specification.

This invention relates to an improved 10 flash-light for the use of photographers, and for this purpose the invention consists of a photographic flash-light which comprises a powder-pan, a powder-receptacle below the pan, means for supplying the 15 powder to the pan, electrodes in said pan, a fuse-wire between the electrodes in the pan for igniting the powder therein.

The invention consists further of certain 20 details of construction which will be fully described hereinafter and finally pointed out in the claims.

In the accompanying drawing, Figure 1 represents a side-elevation, partly in vertical longitudinal section, of my improved 25 photographic flash-light, and Figs. 2 and 3 are side-views of the electrodes screwed into the bottom of the flash-light pan.

Similar reference characters indicate corresponding parts throughout the figures of 30 the drawing.

Referring to the drawing, 6 and 7 represent the electrodes which are screwed through the bottom of the powder-pan 14 so as to project to the interior of the same. 35 The electrodes 6 and 7 are provided preferably with thumb-pieces 16 and 17 at their lower ends and collars 18 up to which the electrodes can be screwed through the bottom of the powder-pan 14. The inner ends 40 of the electrodes 6 and 7 are provided with V-shaped recesses for supporting a fuse-wire, as indicated at 19. The electrode 6 is made larger than the electrode 7, the one serving for connecting with the negative 45 and the other with the positive pole of a battery or other source of electricity 13. To the powder-pan 14 is attached, midway between the electrodes, a flat V-shaped or funnel-shaped body 8 that is supported by 50 its tubular shank 28 in an opening in the bottom of the powder-pan for establishing connection between the powder-pan and a powder-receptacle 10 that is attached to the underside of the pan 14 and filled with magnesium-powder. Alongside of the receptacle 55 10 is arranged a tube 15 through which

the conducting wires from the source of electricity 13 are conducted to the electrodes 6 and 7. A switch 11 is arranged at any suitable point of the tube 15 so as to close 60 the circuit when a spark between the electrodes 6 and 7 for igniting the powder and producing the flash, is to be transmitted. A follower 12 is arranged in the bottom of the receptacle so as to bring the powder 65 in upward direction and closer to a blow-tube 9 which is arranged in the upper part of the receptacle, and by which a sufficient quantity of powder is transferred from the funnel 8 into the pan 14 and thence into 70 contact with the fuse-wire 19. The V-shaped or funnel-shaped body 8 may be made in the required size for permitting the powder to be distributed equally over the same and slightly above the fuse-wire be- 75 tween the electrodes.

The improved flash-light is used by taking hold of the receptacle, closing the switch, and transferring the required quantity of powder required for a flash by the 80 blow-pipe from the receptacle 10 to the funnel-shaped body. As soon as another flash-light is required, another quantity of powder is discharged from the receptacle by means of the blow-pipe onto the funnel- 85 shaped body, and then ignited by the fuse-wire.

I claim:

1. A photographic flash-light apparatus, comprising a powder-pan, threaded electrodes vertically adjustable in said pan, a supply-funnel between said electrodes provided with a tubular shank, a fuse-wire connected with the electrodes and extending between the same and over the supply-funnel, a powder-receptacle attached to the bottom of the powder-pan below the supply-funnel, a blow-pipe extending into said receptacle, conducting wires connecting the electrodes with the source of electricity, and 90 a switch for closing the electric circuit through the fuse-wire. 95

2. A photographic flash-light apparatus, comprising a powder-pan, electrodes threaded in the bottom of and extending into said pan, a supply-funnel between said electrodes provided with a tubular shank, a fuse-wire connected with the electrodes and extending between the same and over the supply-funnel, a powder-receptacle attached to the 100 bottom of the powder-pan below the supply-funnel, a blow-pipe extending into said 110

receptacle, conducting wires connecting the electrodes with the source of electricity, a tube running alongside of said receptacle for the conducting wires, and a switch for closing the electric circuit of the conducting wires and electrodes.

In testimony, that I claim the foregoing

as my invention, I have signed my name in presence of two subscribing witnesses.

CHARLES MYERS.
